United States Patent Office

Des. 184,751
Patented Mar. 31, 1959

184,751

SOFA

John C. McGuire, San Francisco, Calif.

Application September 15, 1958, Serial No. 52,650

Term of patent 14 years

(Cl. D15—11)

FIG. 1

I claim:

The ornamental design for a sofa, as shown.
